CLAIM

The ornamental design for an identification tag, as shown and described.

DESCRIPTION

FIG. 1 is a perspective view of an identification tag of my new design;

FIG. 2 is a front side elevational view of the embodiment of FIG. 1 thereof;

FIG. 3 is a left side elevational view of the embodiment of FIG. 1 thereof;

FIG. 4 is a rear side elevational view of the embodiment of FIG. 1 thereof;

FIG. 5 is a right side elevational view of the embodiment of FIG. 1 thereof, FIG. 5 being a mirror image of FIG. 3;

FIG. 6 is a bottom plan view of the embodiment of FIG. 1 thereof; and,

FIG. 7 is a top plan view of the embodiment of FIG. 1 thereof.

The broken lines of the Figures are for the purpose of illustrating portions of the identification tag and form no part of the claimed design.
